Design No. 3,433, dated March 30, 1869.

DESIGN FOR A TRADE-MARK

The Schedule referred to in these Letters Patent and making part of the same

---

To all whom it may concern:

Be it known that we, SIMON W. DEXTER and DANIEL S. DEXTER, of Pawtucket, in the county of Providence, and State of Rhode Island, have originated and designed a new Design for a Trade-Mark, of which the following is a full, clear, and exact description, reference being had to the accompanying specimen, making a part of this specification.

Our object is to secure a distinctive trade-mark for the different grades of knitting-cotton manufactured by us, as the successors of our late father, Nathaniel G. B. Dexter, who commenced the business in the year 1820, and gave to yarns manufactured under his name, a reputation for excellence throughout the whole country.

In order that purchasers may be able to distinguish

our goods from others, which are put upon the market, in imitation of the same, we adopt, as a trade-mark for our packages of ball-cotton, a label which bears upon its face a portrait of our late father, Nathaniel G. B. Dexter, together with such descriptive words as shall appropriately designate the kind, quality, and colors of the yarns.

What we claim, and desire to secure by Letters Patent, is—

The design for a trade-mark herein set forth.

SIMON W. DEXTER.
DANIEL S. DEXTER.
